(57) **CLAIM**

The ornamental design for a calibration target for medical device, as shown and described.

DESCRIPTION

FIG. 1 is a perspective view of a calibration target for a medical device, showing our new design;

FIG. 2 is a top view of the calibration target for a medical device of FIG. 1;

FIG. 3 is a bottom view of the calibration target for a medical device of FIG. 1;

FIG. 4 is a front view the calibration target for a medical device of FIG. 1;

FIG. 5 is a back view of the calibration target for a medical device of FIG. 1;

FIG. 6 is a left side view of the calibration target for a medical device of FIGS. 1; and,

FIG. 7 is a right side view of the calibration target for a medical device of FIG. 1.

The broken lines in the drawings are for the purpose of illustrating portions of the calibration target for medical device that form no part of the claimed design.
